UNITED STATES PATENT OFFICE.

SAMUEL SMITH, OF PHILADELPHIA, PENNSYLVANIA.

COOKING-STOVE.

Specification of Letters Patent No. 26,298, dated November 29, 1859.

To all whom it may concern:

Be it known that I, SAMUEL SMITH, of the city and county of Philadelphia and State of Pennsylvania, have invented certain new and useful Improvements in Cooking-Stoves; and I do hereby declare the following to be a full, clear, and exact description of the same, reference being had to the accompanying drawing and to the letters of reference marked thereon.

My invention consists, firstly, in a grate with hollow bars communicating with each other and arranged in respect to a perforated box situated at the back of the fire place and having zigzag passages, as fully described hereafter, so that the air by traversing up and down the bars before it passes into the box and traverses the passages of the latter may be thoroughly heated before it passes through the perforation in the box to assist in consuming the gaseous products of combustion; secondly, in certain plates arranged as described hereafter so as to serve the double purpose of connecting together the hollow bars of the grate, and of forming a chamber for heating the air prior to the same being discharged in jets onto the front of the fire.

In order to enable others skilled in the art to make and use my invention, I will now proceed to describe its construction and operation.

On reference to the accompanying drawing which forms a part of this specification, Figure 1 is a sectional elevation of my improved cooking stove. Fig. 2, a front view. Fig. 3, a transverse sectional elevation on the line 1—2, Fig. 1. Fig. 4, the same on the line 3—4 Fig. 1. Fig. 5, a section of the grate on the line 5—6 Fig. 3. Fig. 6, a transverse section of one of the bars of the grate, drawn to the full size.

Similar letters refer to similar parts throughout the several views.

A, represents the side, front and back plates, B, the top plate, and C the bottom plate of the outer casing of my improved cooking stove, D the oven, E the fire place, F the ash pit, G the grate, I the upper flue, J the lower flue, K the rear flue, and H the exit opening communicating with the chimney.

The grate G, is of the curved form common to the grates of ordinary cooking stoves and occupies the usual position in respect to the oven, the fire place, and the

ash pit, the grate however is made of two separate pieces connected together, the upper piece *m*, fitting onto the lower piece *n* as seen in Fig. 6, and both pieces being so constructed and combined as to form hollow bars.

The vertical portion of the hollow grate rests against the inside of the front plate of the stove in which are two holes *i* and *i'*. 65 The hole *i* communicates with the hollow end bar *j*, (Fig. 3) of the grate and the hole *i'* with the hollow end bar *j'*. The external air entering the hole *i* passes down the hollow bar *j* along a passage *k* to the hollow bar *l*, upward through the latter along the passage *q*, into the hollow bar *p* and down this bar into the hollow back L of the fire place. The air entering the hole *i'*, traverses the bar *j'*, passage *k'*, bar *l'*, passage *q'*, 75 from which it also escapes into the hollow back L of the fire place.

It will be seen on reference to Fig. 5, that the several bars of the grate are connected together at the top by the two plates *r* and *s*, between which is a chamber open at the bottom for the free admission of air and communicating through small holes *t* with the interior of the fire place (see Fig. 5). This chamber is separated from the interior of 85 the bars and their communicating passages by suitable partitions, so that the air which traverses the bars cannot gain access to the air chamber between the plates *r* and *s*.

The hollow back L of the fire place has 90 several partitions *u*, forming a zigzag passage which communicates with a horizontal passage or chamber *v*, the latter communicating through a series of perforations with the fire-place so that the air which passes from the hollow bars *p* and *p'*, through the openings *x*, (Fig 4) into the hollow back, 95 must traverse the zigzag passage before it can escape into the fire place through the above mentioned perforations.

In the ash pit F fits a plate *a* forming a chamber *M* into which the air passes through openings in front of the ash pit said openings being covered by a slide *b* so that the admission of air may be regulated 105 or entirely cut off at pleasure.

The chamber *M* communicates through a number of openings with another chamber *N*, situated beneath the grate and communicating either with the hollow back or with 110 the external air through openings at the sides of the stove.

By the peculiar construction of the grate the air must traverse the several bars before it can enter the hollow back and as it is retarded in its passage through the latter it 5 must become heated to such a degree, that when it passes through the perforations in the top of the back it serves efficiently to ignite the carbon intermixed with the products of combustion arising from the fuel.

10 Independent of the jets of heated air discharged into the fuel in the rear of the fire place, similar jets for a similar purpose are discharged from the hot air chamber between the two plates *r* and *s* which serve to 15 connect the hollow bars together.

By making the hollow grate in two pieces *m* and *n* (Fig. 6) the upper piece when injured by close contact with the fire may be removed and replaced by a new upper 20 piece, the lower piece being preserved entire for a length of time by being further from the fire and having air constantly passing in contact with it.

By the air chambers *M* and *N*, and hollow back *L*, the oven is relieved from that excessive heat which the fire places of this 25 class of stoves impart to the front of the

oven, the three chambers serving to separate the fire place from the oven.

I am aware that hollow backs as well as 30 hollow grate bars have been used in connection with cooking stoves, I therefore lay no broad claim to such devices; but

I claim as my invention and desire to secure by Letters Patent—

1. The grate *G* having hollow bars communicating with each other and arranged in respect to the hollow back *L*, and its zigzag passages, as set forth for the purpose specified.

2. The plates *r* and *s* of the grate *G*, when arranged as specified so as to serve the double purpose of connecting the bars of the grate together and forming a chamber for heating the air preparatory to the same being discharged in jets into the front of the fire.

In testimony whereof, I have signed my name to this specification in the presence of two subscribing witnesses.

SAMUEL SMITH.
